CLAIM

The ornamental design for an air fryer basket, as shown and described.

DESCRIPTION

FIG. 1 is an elevated isometric view of an air fryer basket showing the new design;

FIG. 2 is a front isometric view of the air fryer basket shown in FIG. 1;

FIG. 3 is a rear isometric view of the air fryer basket shown in FIG. 1;

FIG. 4 is a right side isometric view of the air fryer basket shown in FIG. 1;

FIG. 5 is a left side isometric view of the air fryer basket shown in FIG. 1;

FIG. 6 is a top view of the air fryer basket shown in FIG. 1; and,

FIG. 7 is a bottom view of the air fryer basket shown in FIG. 1.

The broken lines shown in the appended figures are for purposes of illustrating environmental structures and form no part of the claimed design.

1 Claim, 7 Drawing Sheets
